Ronald R. W.
ATTORNEY

UNITED STATES PATENT OFFICE.

JOE WIEDER, OF NEW YORK, N. Y.

SAMPLE TAB.

Application filed January 22, 1925. Serial No. 3,964.

To all whom it may concern:

Be it known that I, JOE WIEDER, a citizen of the United States, and a resident of 1415 Wilkins Avenue, city of New York, county 5 of Bronx, and State of New York, have invented certain new and useful Improvements in Sample Tabs, set forth in the following specification.

This invention relates to sample holding and displaying tabs adapted to be mounted 10 on a sample card, for the purpose of displaying a number of textile samples.

The object of the invention is to display the samples removably, either as an entirety 15 with said tab, or separately therefrom, to protect each individual sample and to insure its smooth mounting when on display. A further object of the invention is to simplify and cheapen the tab structure for these 20 purposes.

The above will better be understood by the illustrative embodiments of the invention, set forth in the following specification, which should be read in connection 25 with the accompanying drawings, which form a part hereof and to which the claims are directed merely for purposes of illustration.

In the drawing Fig. 1 is a plan view showing two tabs in their relation to a sample cord; Fig. 2 is a section indicated by the line II—II of Fig. 1; Fig. 3 is a cross section in the plane indicated by the line III—III of Fig. 1; Fig. 4 is a plan view of a tab 30 drawn to an enlarged scale; Fig. 5 is a perspective view of a tab body; and Fig. 6 is a fractional view showing a modified window construction for the tab.

A body portion A, preferably of light 40 cardboard or heavy paper, is cut to an outline substantially as indicated in Fig. 5. Attaching ears 1 and 2 extend out from this body portion to provide for the mounting of the assemblage by insertion in slots 3 and 40 45 of a sample card B. A rim-portion 5 of the body portion A, defines one or more windows, 6', 6'', or in fact any desired window construction. Flaps 7 and 8 are also preferably provided along the longitudinal edges of body portion A at the rear. An inner stiffener of stiff material, such as 50 cardboard, is indicated by C. About this stiffener is stretched a textile sample D, its

longitudinal edges 9 and 10 being drawn in toward each other to effect the stretching. The body portion of the textile sample is then faced up against the body portion 55 of the tab and the flaps, 7 and 8, are folded back to clamp the sample tightly against the stiffener and against the rim of said window. The grip of the fingers is sufficient to hold this assemblage together until the entire tab is mounted on a sample card by the insertion of the ears 1 and 2 through the slots 3 and 4. When so mounted 60 the cooperation of the tab with the mounted card B, maintains the clamping of the sample. In Figs. 1 to 5 inclusive, the flange portion of the tab, extends about all four edges of the window, but in Fig. 6 65 it does not extend above the top edge of the window and the sample D shows free at its top edge, but is not free, but as a matter of fact it is mounted and held in place. There is no pasting or gluing of any of the 70 parts of this tab. This permits the tabs to be charged with new samples; the removal and replacement of samples, and their examination in the fingers, all with expedition and dispatch. 75

What I claim and desire to secure by United States Letters Patent is:—

1. A sample tab, comprising an ear-ended mount of flexible material, the body-portion of which has a window; an underlying inturned flap at the edge of said body portion; an inner stretcher of flat material; in combination with a textile sample adapted to be folded about the said stretcher and to lie between said stretcher and said body-portion having said window, with said flap clamping the said sample against said stretcher and said body-portion, whereby a smooth partially protected display of said sample through said window is made. 85

2. The structure set forth in claim 1 and further characterized by the fact that said body portion has two flaps underlying the stretcher and serving to assist in holding the sample. 90

In testimony whereof I have signed my name to this specification, this 17 day of January, 1925.

JOE WIEDER.
